UNITED STATES PATENT OFFICE

JOSEPH ARTHUR PAYETTE, OF ATTLEBORO, MASSACHUSETTS, ASSIGNOR TO GENERAL PLATE COMPANY, OF ATTLEBORO, MASSACHUSETTS, A CORPORATION OF MASSACHUSETTS

ELECTRICAL CONTACT AND THE MANUFACTURE THEREOF

Application filed February 26, 1932. Serial No. 595,265.

This invention relates to electrical contacts, and with regard to certain more specific features, to contacts for use especially with thin blade material.

5 Among the several objects of the invention may be noted the provision of an electrical contact of the class described which includes a reduced quantity of precious metal, without, however, decreasing the contacting area of such metal; the provision of a contact of the class described which eliminates the necessity of punching, riveting, and like operations for affixing precious metal to the thin blade material; a contact of the class described wherein the precious metal is securely affixed to the thin blade material; a contact of the class described wherein the precious metal is maintained in improved electrical contact relationship with the thin blade material; the provision of a method of manufacturing contacts of the class described wherein only simple operations, such as rolling, pressing and the like are involved; and the provision of a contact and a method of manufacturing the same which is economical and simple. Other objects will be in part obvious and in part pointed out hereinafter.

The invention accordingly comprises the elements and combinations of elements, steps and sequence of steps, features of construction and synthesis, and arrangements of parts, which will be exemplified in the structures and processes hereinafter described, and the scope of the application of which will be indicated in the following claims.

In the accompanying drawings, in which are illustrated several of various possible embodiments of the invention,

40 Fig. 1 is an enlarged cross section of a sheet of thin blade material;

Fig. 2 is a cross section of the material of Fig. 1 after a first operation has been performed thereon;

45 Fig. 3 is a top plan view of the thin blade material illustrated in Fig. 2;

Fig. 4 is a cross section similar to Fig. 2 illustrating the blade material after a second operation has been performed thereon;

50 Fig. 5 is a top plan view of the blade ma-

terial after the operation indicated in Fig. 4 has been performed thereon;

Fig. 6 is a bottom plan view of the blade material after the operation indicated in Fig. 4 has been performed thereon;

55 Fig. 7 is a cross section illustrating the first step in the application of precious metal to the blade material;

Fig. 8 is a cross section similar to Fig. 7 illustrating the final positioning of the precious metal on the blade material;

60 Fig. 9 is a top plan view of the assembly illustrated in Fig. 8;

Fig. 10 is a trimetric view of a completed thin blade contact;

65 Fig. 11 is a view similar to Fig. 5 illustrating an alternative embodiment of the invention;

70 Fig. 12 is a cross section similar to Fig. 8 illustrating another embodiment of the invention; and,

Fig. 13 is a cross section similar to both Figs. 8 and 12, illustrating yet another embodiment of the invention.

75 Similar reference characters indicate corresponding parts throughout the several views of the drawings.

The heretofore-used construction of thin blade contacts, which comprises, generally, the riveting of a heavy rivet of precious metal into the end of a thin blade, is disadvantageous in several respects. In the first place, only a relatively small area of good electrical contact is secured between the precious metal rivet and the thin metal blade, thus decreasing the electrical conductivity. In the second place, in order to dissipate heat, it is necessary that a heavy rivet be used, and this requires a considerable amount of precious metal in the rivet, thus increasing the cost considerably. In the third place, the riveting operation is uneconomical and impractical. In the fourth place, the loosening of the rivets, which takes place during use, permits oxidation to enter between the rivet and the strip, causing overheating and frequently total destruction of the contact.

90 The present invention overcomes all of the foregoing difficulties, and provides a thin blade contact wherein the maximum area of

contact is provided between the precious metal and the thin blade, thus increasing the electrical conductivity of the assembly, and at the same time permits the use of the precious metal in strip or sheet form, or as a composite metal comprising base metal and a relatively thin layer of precious metal, without necessitating the specialized pre-formation of rivets therefrom.

10 Referring now more particularly to Fig. 1, there is illustrated at numeral 1, in considerably enlarged form, a sheet of thin-blade material. The material 1 usually comprises a spring bronze or the like but might equally well be any other good electrical conducting metal, such as spring copper, brass, or the like.

20 The first operation of the present invention comprises turning over or rolling the edge of the sheet 1 to form a bead or overlap 2 (see Figs. 2 and 3). It will be understood that this operation may easily be performed either with dies or rollers or the like, and is comparatively simple to carry out.

25 After the bead 2 has been formed on the sheet 1 it is passed through a pair of rollers or the like which are so formed to provide a series of indentations or depressions or the like 3 on either or both sides of the bead 2. 30 Figs. 5 and 6 illustrates the conformation of such indentations on the top and bottom sides of the sheet 1. Instead of the simple, corrugated form of indentations 3, the rolls may be arranged to produce a knurling or the like 35 such as illustrated in Fig. 11. Any suitable conformation may be used, the purpose of the indentations 3 being merely to supply a firm holding region for the precious metal later to be applied.

40 With the sheet 1 prepared as in Fig. 4, the next step comprises the affixing of the precious metal contact material. Such precious metal contact material is originally provided in the form of a strip which is bent to a U-45 conformation illustrated at numeral 4 in Fig. 7. The precious metal 4 is placed in position around the bead 2 as illustrated in Fig. 7 and then passed through a pair of compression rollers or the like. The effect of the compression rollers is to cause the precious metal 4 to flow into the indentations 3 and to surround the bead 2 in such a manner that the precious metal 4 secures itself to the sheet 1. The final position of the precious metal is 50 illustrated in Fig. 8. The shoulder formed by the edge of the bead 2 indicated at numeral 5, prevents the precious metal 4 from being pulled off the sheet 1, while the indentations 3 keep such precious metal from moving laterally on the sheet 1. Thus the precious metal is thus securely affixed to the strip without soldering or the like, and without necessitating a riveting or like procedure.

Fig. 9 is a plan view of the finished contact material illustrated in Fig. 8. This mate-

rial is a blank from which the contact strips are cut, as along the dot and dash lines indicated by numeral 6. The final form of an individual contacting strip is illustrated in Fig. 10.

70 It will be seen that an electrical joint of high conductivity is achieved, because the area of contact between the precious metal 4 and the strip 1 is quite large. Further, the joint is of a permanent, reliable nature, thus 75 eliminating the danger of loose connections and the like.

By the term "precious metal" herein is meant the usual contact metals, such as silver, gold, platinum and the like, or plated precious 80 metals. It will of course be understood that the present invention is not limited to any one of these metals, or to any metal for that matter.

85 For instance, it is not necessary that the entire contact be made of a single piece of precious material 4. In Fig. 12, for example, is illustrated an alternative embodiment, in which the precious contact portion proper comprises a soft bronze or like layer 7 on 90 which has been plated or rolled or otherwise affixed a thin layer 8 of contact metal such as silver. In this instance, as in the others, the contacting material is securely affixed with large conductive area to the strip or 95 sheet 1.

Fig. 13 illustrates an embodiment somewhat similar to the embodiment of Fig. 12. In this instance, the precious metal plated area is confined to one side of the contact, 100 as at numeral 9, and the quantity of precious metal (and total cost) is thereby reduced. Inasmuch as most contacts are used on but one side, this Fig. 13 embodiment is the most practical, commercially, of the several 105 embodiments illustrated.

110 In view of the above, it will be seen that the several objects of the invention are achieved and other advantageous results attained.

115 As many changes could be made in carrying out the above constructions without departing from the scope of the invention, it is intended that all matter contained in the above description or shown in the accompanying drawings shall be interpreted as illustrative and not in a limiting sense.

I claim:

1. An electrical contact comprising a blade of relatively thin metal, said blade being 120 turned over at one end forming a bead, and a metal contact of U-conformation, compressed around said bead.

2. An electrical contact comprising a blade of relatively thin metal, said blade having a 125 bead at one end thereof, said bead having indentations thereon, and a metal contact of U-conformation surrounding said bead and extending into said indentations.

3. An electrical contact comprising a blade 130

of relatively thin metal, said blade having a bead at one end thereof forming a shoulder, said bead having indentations thereon, and a metal contact of U-conformation surrounding said bead, said contact being compressed behind said shoulder, whereby relative motion lengthwise of the blade is prohibited, and into said indentations, whereby relative motion crosswise of the blade is prohibited.

10 4. An electrical contact as set forth in claim 3, in which the indentations comprise corrugations crosswise of the bead.

5. An electrical contact as set forth in claim 3, in which the indentations comprise 15 knurlings.

6. An electrical contact as set forth in claim 3, in which the indentations are provided on both sides of the bead.

7. An electrical contact as set forth in 20 claim 3, in which the metal contact comprises precious metal.

8. An electrical contact as set forth in claim 3, in which the metal contact comprises base metal having a layer of precious metal 25 on its exterior surface.

9. An electrical contact as set forth in claim 3 in which the metal contact comprises a base metal having a layer of precious metal on one of its exterior surfaces.

30 10. The method of securing precious metal or like contacts to thin blade material which comprises forming a bead along one side of the blade material, forming a series of indentations in said bead, positioning a strip 35 of precious metal of U-conformation around said bead, and compressing said strip until it flows around said bead and into said indentations.

40 In testimony whereof, I have signed my name to this specification this 8th day of February, 1932.

JOSEPH ARTHUR PAYETTE.
